(57) **CLAIM**

The ornamental design for a locking device, as shown and described.

DESCRIPTION

FIG. 1 is a left, front, perspective view of my locking device in a closed position.

FIG. 2 is a front elevation view thereof.

FIG. 3 is a rear elevation view thereof.

FIG. 4 is a right side elevation view thereof.

FIG. 5 is a left side elevation view thereof.

FIG. 6 is a top plan view thereof,

FIG. 7 is a bottom plan view thereof.

FIG. 8 a left, front, perspective view of my locking device in an open position.

FIG. 9 is a front elevation view thereof.

FIG. 10 is a rear elevation view thereof.

FIG. 11 is a right side elevation view thereof.

FIG. 12 is a left side elevation view thereof.

FIG. 13 is a top plan view thereof; and,

FIG. 14 is a bottom plan view thereof.

The dash-dash lines indicate environmental and disclaimed portions to which no claim is made. The surfaces are lined for contour.
